(57) **CLAIM**

The ornamental design for a cassette for a digital slide scanner, as shown and described.

DESCRIPTION

FIG. 1 is a front view of a cassette for a digital slide scanner of the present invention.

FIG. 2 is a rear view thereof.

FIG. 3 is a top plan view thereof.

FIG. 4 is a bottom view thereof.

FIG. 5 is a right side view thereof.

FIG. 6 is a left side view thereof.

FIG. 7 is a perspective view thereof.

FIG. 8 is an enlarged view showing a portion of FIG. 1 defined by the line 8-8.

FIG. 9 is an enlarged view showing a portion of FIG. 5 defined by the line 9-9.

FIG. 10 is an enlarged view showing a portion of FIG. 6 defined by the line 10-10.

FIG. 11 is an enlarged view showing a portion of FIG. 7 defined by the line 11-11.

FIG. 12 is an enlarged cross-sectional view taken along the line 12-12 in FIG. 8.

FIG. 13 is an enlarged cross-sectional view taken along the line 13-13 in FIG. 9; and,

FIG. 14 is an enlarged cross-sectional view taken along the line 14-14 in FIG. 9.

The features shown in broken lines depict environmental subject matter only and form no part of the claimed design. The alternating long and short dashed lines indicate bounds of the claimed design and form no part thereof.

1 Claim, 14 Drawing Sheets
